UNITED STATES PATENT OFFICE.

EDOUARD ERNEST FERDINAND LEPARMENTIER, OF DIEPPE, FRANCE.

COMPOUND BARGE.

1,303,690.

Specification of Letters Patent. Patented May 13, 1919.

Application filed March 5, 1918. Serial No. 220,643.

To all whom it may concern:

Be it known that I, EDOUARD ERNEST FERDINAND LEPARMENTIER, a citizen of the Republic of France, residing in Dieppe, Seine-
Inférieure, France, have invented certain
new and useful Improvements in Compound
Barges, of which the following is a specific-
cation.

The invention relates to a marine barge
formed by coupling together two or more
barges which are both internally and exter-
nally cylindrical such as has been described
in application for United States Letters
Patent No. 185,704, filed August 11, 1917.

The invention is illustrated in the accom-
panying drawing, showing the combination
of two barges situated side by side.

Figure 1 is a side elevation of the barge;
Fig. 2 is a transverse section thereof on a
larger scale;

Fig. 3 is a plan thereof partly in hori-
zontal section;

Figs. 4 and 5 are cross-sectional diagrams
illustrating the effect of flooding certain
compartments;

Fig. 6 is a detail view drawn to an en-
larged scale of a hatchway partly in section
as viewed from its end.

Fig. 7 is a plan of the said hatchway.

Referring to Figs. 1, 2 and 3 the two cylind-
rical hulls are marked A and B respec-
tively. They are connected by sheet iron
plates *a*, *b*, *c* which are perfectly tight.

It has been shown in the said application
that barges consisting of a cylindrical hull,
such as A or B, are substantially unsinkable.
The compound barge consisting of these ele-
ments and shown in the accompanying draw-
ing is also practically unsinkable.

For this purpose the two hulls are always
strictly cylindrical internally, and a wafer-
ballast chamber subdivided by tight trans-
verse partitions *d* is constructed between
them in the part limited by the partitions *b*
and *c*. In this manner the hulls always pre-
serve for any liquid cargoes a developed in-
terior metacenter reduced to a point.

It follows that for all such cargoes the
point of support at any inclination of the
vessel is identical with the center of each
cylindrical hull which is the geometrical po-
sition of all interior metacenters. The cen-
ter of support of the whole cargo thus re-
mains constantly on the intersecting line of
two planes of symmetry of the vessel X X
and Y Y and its constancy being thus as-

sured, the resistance of the vessel to being
capsized is equally assured. The same
property exists with homogeneous solid car-
goes for the center of gravity of the whole 60
cargo is necessarily situated below the center
of volume of the hulls.

The arrangement of the water-ballast be-
tween the hulls A and B also has the ad-
vantage that access can be attained to the 65
plates of the water ballast chamber so that
these can be easily repaired.

Moreover, the external concavity of the
lateral walls and the fact that they approach
each other upward diminishes the metacen-
tric radius of the liquid keels within the
ballast so as to ameliorate the disturbance of
the stability of the vessel in rolling move-
ments. This diminution is due to the fact
that the moment of inertia for the several 75
levels of the liquids introduced into the
water-ballast is diminished. It is known in-
deed that the metacentric radius of this in-
ternal keel is given by the relation $\frac{1}{V}$ when 80

I is the moment of inertia of the internal flo-
tations and V the volume of the ballast.

The water ballast also comprises hori-
zontal transverse baffle plates which are not
tight and complete the connection of the 85
hulls and break up the shocks and blows of
the heaving ballast.

Finally, the part comprised between the
plates *a* and *c* forms a tight passage afford-
ing room for movement from end to end 90
under shelter. This passage contains par-
ticularly loading and navigating apparatus,
such as winches, capstans, or the like. It also
forms a storage compartment, if necessary,
for the equipment and service of the vessel 95
generally.

Thus, the vessel has the same qualities as
the barge described in the said application
for United States Letters Patent. It is con-
stituted of elements completely capable of 100
being developed and it is practically in-
capable of being submerged and capsizing.
Moreover, it shows great security against
torpedoes and other damage since any acci-
dental to one of the hulls does not imperil the 105
existence of the vessel which always re-
mains sufficiently afloat by reason of the re-
serve of flotation provided by the space be-
tween the hulls. This is illustrated by Figs.
4 and 5 which show the heeling consequent 110
on the blowing open of a portion of the
compartments of one hull; in Fig. 4 it being

assumed that four compartments are flooded and in Fig. 5 that six compartments are flooded.

The hatches, when their weight and bulk exceed a certain limit are operated by the following device:—

- The cover D is constructed to receive four removable grooved wheels e rolling on longitudinal rails f. These wheels are put in place in the following manner:—A screw g working in a nut h fixed to the cover is supported on a bearing i fixed to the vessel and lifts the end of the cover sufficiently to allow the two wheels e which are nearest to the screw g to be brought into position and mounted on the cover by inserting their pivots or axles j in a hanger k; the rails f can then be engaged in the grooves of the wheels by unscrewing the screw g.
- 20 A similar operation at the other end of the cover places the latter on its four rollers and thus allows longitudinal displacement of the cover. Reverse operation places the cover in the position in which it closes the 25 hatchways.

To prevent the cover from running free on the rails during the operation, a brake l holds it in place.

Having now fully described my said invention and the best means I know of carrying the same into practical effect, I claim:—

1. A compound barge comprising a number of individual barges consisting of hulls which are cylindrical both internally and externally, and a framework connecting adjacent barges, the said framework also being internally and externally of cylindrical contour and comprising a water ballast and a storage compartment.
- 40 2. A compound barge comprising two substantially cylindrical hulls and a framework connecting them comprising an upper arched plate, a lower convex plate and an intermediate plate or deck, the space between the upper and intermediate plates constituting a longitudinal passage, and the

space between the intermediate and lower plates constituting a water ballast chamber.

3. A compound barge comprising a plurality of individual barges of approximately cylindrical form arranged side by side, and an intervening frame-work connecting them comprising top and bottom plates and inclosing a chamber constituting an intermediate hull.

4. A compound barge comprising a plurality of individual barges of approximately cylindrical form, each sub-divided by transverse bulk-heads into multiple compartments, said barges arranged side by side, and an intervening frame-work connecting them comprising top and bottom plates, and inclosing a chamber forming an intermediate hull.

5. A compound barge comprising a plurality of individual barges of approximately cylindrical form, arranged side by side, and a frame-work connecting them consisting of top and bottom plates constituting an intermediate hull with its lower portion subdivided by transverse bulk-heads into successive ballast compartments.

6. A compound barge comprising a plurality of individual barges of approximately cylindrical form, arranged side by side, and a frame-work connecting them consisting of top and bottom plates constituting an intermediate hull, and an intermediate plate dividing such hull into a lower chamber which may contain ballast, and an upper chamber constituting a longitudinal deck, and transverse bulk-heads dividing such lower chamber into successive ballast compartments.

In witness whereof, I have hereunto signed my name in the presence of two subscribing witnesses.

EDOUARD ERNEST FERDINAND LE PARMENTIER.
